UNITED STATES PATENT OFFICE.

JOSEPH SOSS, OF NEW YORK, N. Y.

HINGE.

Application filed November 21, 1921. Serial No. 516,593.

To all whom it may concern:

Be it known that I, JOSEPH Soss, a citizen of the United States, and residing at New York, in the county of New York and State of New York, have invented certain new and useful Improvements in Hinges, of which the following is a specification, such as will enable those skilled in the art to which it appertains to make and use the same.

This invention relates to hinges and particularly to what are known as invisible hinges, and the object of the invention is to provide an improved butt construction for hinges of this class whereby the attachment of the hinge butts to a door or swinging member and door frame or stationary support may be materially simplified as well as the proper alining or mounting of a door or swinging member in a door frame or support; and with this and other objects in view the invention consists in a hinge of the class and for the purpose specified which is simple in construction and operation and efficient in use.

The invention is fully disclosed in the following specification, of which the accompanying drawing forms a part, in which the separate parts of my improvement are designated by suitable reference characters in each of the views, and in which:—

Fig. 1 is a partial side view of a door and door frame showing my improved lock construction mounted therein with part of the construction broken away and in section;

Fig. 2 a side edge view of a door frame with the door in an open position and showing my improved hinge mounted in connection therewith and in an extended position;

Fig. 3 a partial section on the line 3—3 of Fig. 2;

Fig. 4 a partial section on the line 4—4 of Fig. 1; and,

Fig. 5 a partial section on the line 5—5 of Fig. 3.

In the drawings I have indicated at 10 a part of a door frame or other stationary support, and at 11 a part of a door or swinging member, and my improved hinge construction 12 is adapted to be mounted in connection with the door frame 10 and door 11 as hereinafter set out.

The hinge 12 comprises two cylindrical

hinge butts 13 and 14, each of which are of the same general form and construction as clearly shown and are adapted to be passed into holes 15 and 16 drilled in the adjacent side faces of the door frame 10 and door 11, and said cylindrical hinge butts are held in position by nails, screws or other attaching devices 17 passed angularly through the opposite sides of the butts 13 and 14 and into the door 10 and door frame 11, as clearly shown in Figs. 1, 2 and 5 of the drawings.

Each of the hinge butts 13 and 14 are provided with apertures 18 which extend longitudinally through the butts, and the top and bottom walls of said apertures are provided with elongated grooves or recesses 19, and pivotally mounted within the apertures 18 of the hinge butts 13 and 14 as shown at 20 are links 21 and 22, the links 21 being pivoted within the butt 14, and in the construction shown two links 21 are employed and two links 22, but it will be understood that any desired number of said links may be provided.

The links 21 and 22 are substantially L-shaped in form, or are provided with short arms 23 and longer arms 24 arranged at an angle to the short arms 23, and a pivot pin 25 is passed through the links 21—22 where the arms 23 and 24 join, as clearly shown in Figs. 3 and 4 of the drawings, and the arms 24 of the links 21 and 22 are provided with offset portions 26 through which pins 27 pass, said pins extend beyond said links into the groove or recesses 19 in which they are adapted to operate to guide the movement of the links 21 and 22.

The pivot pins at 20 in the separate links are preferably of the construction shown in detail in Fig. 5 of the drawings, said pivot pins being headed at one end as shown at 28 and provided at the other end with hook-shaped fingers 29 which rest in recessed portions in the outer faces of the hinge butts 13 and 14, and said hook-shaped portions serve to retain the pins in proper position as well as to reinforce and strengthen the same as well as the body of the hinge butts.

It will be noted that the distinctive feature of the invention consists in providing hinge butts, the outer faces of which, or the general form of which, are similar or

- approximately similar to that of a cylinder, and all that is necessary to do in mounting the hinges in proper position is to bore or drill a hole or holes in predetermined places 5 in the door frame and door, and set or place the hinge butts in said holes so bored or drilled and secure the same in such position by nails, screws or other attaching devices. Heretofore it has been customary 10 to provide a door and door frame with rectangular or irregularly shaped recesses which were either chiseled into the door and door frame or machined therein, or stamped or molded therein, depending upon the material 15 of which the door and door frame was constructed, but in all such cases the difficulty arises in the proper formation of the recesses to receive the hinge butts as well as the proper alinement of the door 20 by locating or forming said recesses properly, but with my improved construction all that is necessary is to fix upon the door and door frame a center and to drill, bore or otherwise form a cylindrical hole therein, 25 the axis or center of which will be regulated by said centers, and while I have shown in the accompanying drawings hinge butts which are composed of solid material or metal and are fashioned to the desired 30 form by machining, die-casting or otherwise. It will be understood that said hinge butts may be formed in any desired manner, and it must be also borne in mind that I am not necessarily limited to the specific 35 form, construction and arrangement of the invisible hinge elements of the hinge herein shown and described, namely, the links 40 and 22, and various other changes in and modifications of the construction may 45 be made, within the scope of the appended claims, without departing from the spirit of my invention or sacrificing its advantages.
- Having fully described my invention, what I claim as new and desire to secure 50 by Letters Patent, is:—
1. An invisible hinge of the class described the butts of which are cylindrical in form to facilitate their mounting in a stationary support and swinging member.
  2. An invisible hinge of the class described comprising movably connected hinge butts, said hinge butts being cylindrical in form whereby they may be mounted in holes or recesses of similar form in a stationary 55 support and swinging member.
  3. An invisible hinge of the class described comprising movably connected hinge butts, said hinge butts being cylindrical in form whereby they may be mounted in holes or recesses of similar form in a stationary support and swinging member, and means for securing said hinge butts in their supports.
  4. An invisible hinge of the class described, comprising cylindrical hinge butts 60 adapted to be mounted in correspondingly formed bores or recesses in a stationary support and swinging member, and hinge elements connecting said hinge butts and adapted to be contained within said hinge butts when the swinging member is in its closed position.
  5. An invisible hinge of the class described, comprising cylindrical hinge butts adapted to be mounted in correspondingly 75 formed bores or recesses in a stationary support and swinging member, hinge elements connecting said hinge butts and adapted to be contained within said hinge butts when the swinging member is in its closed position, and means passed through said hinge butts and into the stationary support and swinging member for securing said hinge butts in position.
  6. An invisible hinge of the class described for mounting a swinging member 80 and stationary support, said swinging member and stationary support being provided with cylindrical bores or recesses, the hinge being provided with butts of approximately cylindrical form and adapted to be placed in the bores or recesses of said stationary support and swinging member, means for securing said hinge butts in position, and hinge elements mounted in connection with the separate hinge butts for connecting the 85 same with one another.
  7. An invisible hinge of the class described comprising butts of approximately cylindrical formation and provided with apertures, links pivotally mounted in connection with said butts and movable in the apertures thereof, said links being pivoted together, and means for guiding the links pivoted to one hinge butt in the other of said 90 hinge butts.
  8. An invisible hinge of the class described comprising butts of approximately cylindrical formation and provided with apertures, links pivotally mounted in connection with said butts and movable in the apertures thereof, said links being pivoted together, means for guiding the links pivoted to one hinge butt in the other of said 95 hinge butts, and means whereby said hinge butts may be mounted in connection with 100 suitable supports.
  9. An invisible hinge of the class described comprising butts of approximately cylindrical formation and provided with apertures, links pivotally mounted in connection with said butts and movable in the apertures thereof, said links being substantially L-shaped in form and being pivoted together, and means for guiding the free end 105 portions of said links in the separate butts 110 of the hinge.
  10. An invisible hinge of the class described comprising butts of approximately cylindrical formation and provided with apertures, links pivotally mounted in connection 115 with said butts and movable in the apertures thereof, said links being substantially L-shaped in form and being pivoted together, and means for guiding the free end portions of said links in the separate butts 120 of the hinge.

nection with said butts and movable in the apertures thereof, said links being substantially L-shaped in form and being pivoted together, the walls of the apertures of said hinge butts being provided with grooves, and pins passed through the free end portions of said links and adapted to operate in said grooves for guiding said links in said hinge butts.

In testimony that I claim the foregoing 10 as my invention I have signed my name this 18th day of November, 1921.

JOSEPH SOSS.
